United States Patent Office.

D. IRVING HOLCOMB, OF HENRY COUNTY, IOWA.

Letters Patent No. 97,920, dated December 14, 1869.

IMPROVEMENT IN FRUIT-JARS.

The Schedule referred to in these Letters Patent and making part of the same.

To all whom it may concern:

Be it known that I, D. IRVING HOLCOMB, of the county of Henry, and State of Iowa, have invented a new and useful Improvement in "Fruit-Preserving Jars;" and I do hereby declare that the following is a full, clear, and exact description thereof, reference being had to the accompanying drawings, and to the letters of reference marked thereon.

The nature of my invention consists in providing an economical air-tight fruit-preserving jar, which can be easily and speedily closed without the use of wax or other cement, and which can be opened instantaneously without injury to any of its parts, all of which can be used as often as required, without alteration or repair.

Heretofore, the great drawback to preserving quantities of fruit for household use or shipment has been the comparatively great expense of good preserving-jars, and the disappointment experienced as a result of using cheap but worthless ones. Many efforts have been made to produce a jar combining in itself the maximum of usefulness with the minimum of cost, but heretofore without success, though some valuable improvements tending in that direction have been produced.

My improved jar possesses these desirable qualities in an eminent degree, as it is perfectly air-tight, easily closed and opened, and can be produced at a cost one-third less than any really good jar now in the market.

In the accompanying drawings—

Figure 1 is an elevation of the jar, uncovered.

Figure 2, a plan of the same.

Figure 3, an elevation of the jar, when covered and clamped.

Figure 4, a plan of the same on the line $z-z$.

Figure 5, a perspective view of the metal cap.

Figure 6, the wire fastener or yoke.

A represents a fruit-jar, of glass or other suitable material, made with a wide flat surface or shoulder-bed at B, to receive a flat rubber ring, C, which is held in its place by an upright projection forming the mouth of the jar.

D is a flanged cap of thin metal, made to fit as a cover for the mouth of the jar, with its flanged rim

resting on the rubber ring C, and having projections or supporting-lugs d on its upper surface, for the support and bearings of the wire fastener E, which is a piece of wire bent into the shape of a yoke, its extremities fitting tightly on the shoulder of the jar, and pressing the metal cap D downward directly over the rubber ring C and shoulder of the jar, thereby avoiding the common difficulty of springing metallic caps by central pressure.

The cap D is japanned on its inner surface to prevent its corroding.

I prefer this method of closing fruit-jars by an independent wire fastener, whose pressure is brought to bear directly on the flange of the cap where it rests upon the rubber ring, to any fastener, whether attached to or independent of the cap, whose pressure is brought to bear on the centre of the cap, for the reason that it is at the point of contact between the flange of the cap and the rubber ring that pressure is essential, and not at the centre of the cap, where it may have the effect of springing the flange and permitting air to pass between it and the rubber.

And further, by means of an independent wire fastener, and the supporting-lugs on the cap, the degree of pressure can be regulated by bending the wire more or less, and applied at the proper point, that is, immediately on the rubber ring, at the outer edge of the metal cover, in direct line with the shoulder-bed of the jar.

The operation of my invention is easy and simple. When the jar is filled, I place the rubber ring on the flat surface B, put on the cap D, and press the wire E with the thumbs into its position between the projections or supporting-lugs d, reversing the operation when it is desired to open the jar.

I claim the metal cap D, provided with the projections or supporting-lugs d, in combination with fastener E, ring C, and jar A, the whole constructed and operating substantially as and for the purpose specified.

D. IRVING HOLCOMB.
